UNITED STATES PATENT OFFICE.

GLEN W. MORGAN, OF ALHAMBRA, CALIFORNIA, ASSIGNOR TO BROWN VALVE & MANUFACTURING COMPANY, OF ALHAMBRA, CALIFORNIA, A CORPORATION OF CALIFORNIA.

FOOT-OPERATED VISE WITH MULTIPLIED LEVERAGE.

Application filed October 4, 1926. Serial No. 139,363.

My invention relates to bench vises and particularly to foot-operated types of vises in which the movable jaw is gripped against the work by the operation of a foot pedal.

5 It is an object of this invention to provide a foot-operated vise having a powerful grip.

10 The ordinary foot-operated vise has only a single lever for causing the gripping of the movable jaw with the work. When heavy action is to be done on the work, the grip obtained by use of this lever is insufficient to hold the work. I have found that by using a secondary lever, having considerable leverage, for moving the main lever so that a powerful grip is obtained on the work, a superior vise capable of heavy duty is provided.

15 It is accordingly an object of this invention to provide a foot-operated vise having a main lever for operating the movable jaw so as to grip the work sufficiently to hold it in place, and a secondary lever for further operating said main lever so as to strongly grip the work.

20 Other objects and advantages of the invention will be made evident hereinafter.

Referring to the drawings which are for illustrative purposes only,

25 Fig. 1 is a front elevation of a foot-operated vise embodying the features of my invention.

Fig. 2 is a view partially sectioned taken substantially on the line 2—2 of Fig. 1.

30 Fig. 3 is an enlarged fragmentary view of the foot-operated mechanism, this view showing the position of the parts when the movable jaw is in a non-gripping position.

Fig. 4 is a view similar to Fig. 3 showing 35 the parts in the positions they occupy when the movable jaw is in a gripping position.

Fig. 5 is a section taken on the line 5—5 of Fig. 4.

Fig. 6 is a section taken on the line 6—6 40 of Fig. 4.

Fig. 7 is a section taken on the line 7—7 of Fig. 2.

Fig. 8 is a section taken on the line 8—8 45 of Fig. 2.

50 Referring particularly to Figs. 1 and 2, my invention provides a body 11 having a stationary jaw 12 formed at the forward part thereof. The body 11 is provided with side flanges 14 which are supported by a

55 bench 15, there being suitable bolts 16 for securing the body in place. Extending downward from the forward part of the body 11 in front of the bench 15 is a projection 17 having a socket 18 into which the upper end of a column 19 is held. The lower end of the column 19 extends into a socket 21 formed in the upper part of a foot casting 22. The foot casting 22 is attached to a floor 24 by means of an attachment member 25.

60 My invention provides a movable jaw member 27. The movable jaw member 27 has a movable jaw 28 which cooperates with the stationary jaw 12. The member 27 includes a bar portion 29 which is preferably 65 rectangular in cross section as illustrated in Fig. 7, and which extends through a horizontal opening 31 formed in the body 11, this horizontal opening 31 also being rectangular in cross section. The extended end 70 of the bar 29 is provided with a stop pin 32 which is adapted to engage the back end of the body 11 for preventing the movable jaw member 27 from being removed from the body 11.

75 A pivot pin 34 is supported by the body 11 in a cavity 35 formed directly below the horizontal opening 31. Pivoted on the pivot pin 34 is a link 36. The opposite end of the link 36 is pivotally attached to a clevis 80 member 38 by means of a pin 39. Also pivoted to the clevis member 38 by means of the pin 39 is a link 40. The link 40 is provided with a clevis 41 which surrounds the end of the link 36. The other end of the link 40 is curved upward, as shown, and has a pin 43 extended therethrough. The ends of the pin 43, as shown in Figs. 2 and 7, extend into horizontal slots 44 formed in the body 11 on opposite sides of the cavity 35. 85 This arrangement permits the right end of the link 40 to move only in a horizontal direction. The right end of the link 40 is provided in the form of a clevis 45 and supported by the pin 43. Between the arms 90 of the clevis 45 is a weighted pawl 47. When the parts are in the position shown by full lines in Fig. 2, the weighted pawl 47 engages a stop 50 of the body 11, thus holding the pawl out of engagement with a rack 51 95 placed in a cavity 52, which cavity 52 is formed in the lower face of the bar 29.

100 Extending rearward from the projection

17 is a pair of spaced lugs 55 which support a pin 56. Pivoted on the pin 56 is a main operating arm 57. The lower end of the main operating arm 57 is provided in the form of a main foot pedal 58 which extends through an opening 59 formed in the foot casting 22. The main operating arm 57 is resiliently retained in the position shown in full lines in Fig. 2 by means of a compression spring 60 which is compressed between a lug 61 of the main operating arm 57 and the projection 17. Extending from the main operating arm 57 adjacent to the pivot pin 56 are lugs 63 which support a pin 64 on which an adjustment screw 65 is pivotally supported. The adjustment screw 65 is threadedly secured to the clevis member 38.

The operating arm 57 is capable of a movement from the position shown in full lines in Fig. 2 into the position indicated by dotted lines 67. When this movement takes place, the clevis member 38 is moved upward so as to move the links 36 and 40 nearer to alignment. Since the left end of the link 36 is fixed and the right end of the link 40 is not, the right end of the link 40 moves in a rightward direction. When such a movement takes place the pawl 47 is moved from engagement with the stop 50 and will thus swing into engagement with the rack 51. After this engagement the movable jaw member 27 may be moved thereby in a rightward direction.

Referring now particularly to Figs. 3 to 6 inclusive, the foot casting 22 carries a cross shaft 70 on which a release lever 71 is pivoted, the release lever 71 having a lug 72 which surrounds a central part of the shaft 70. The release lever 71 extends forwardly from the shaft 70 through the opening 59, and formed at the front part thereof is a release pedal 73 which is offset as illustrated in Fig. 6, so that it extends to one side of the main pedal 58. That portion of the release lever 71 which is located in the opening 59 is provided with a pair of spaced walls 75 which support a pin 76. Carried by the pin 76 between the walls 75 is a pinion 77. Formed on the lower part of the main operating pedal 58 is an arcuated rack 78. The arcuated rack 78 is formed on a line generated around the center of the shaft 56 on which the main operating arm 57 is pivoted.

The lower part of the foot casting 22 provides a cavity 79 in which a spring 80 is compressed. The spring 80 engages a balance plate 81 which is forced against a formation 82 of the release lever 71. The spring 80 holds the release lever in the position shown in Figs. 1 to 4 inclusive, so that the pinion 77 may engage the rack 78 when the main operating arm 57 is in the position indicated by dotted lines 67 in Fig. 2 and as shown in Fig. 4. The release lever

carries lock dogs 84 and 85 which are spring-actuated and which engage the pinion 77 so that it cannot be rotated in a direction to permit the main operating arm 57 to move from the position shown in Fig. 4 into the position shown in Fig. 3, or from the dotted line position 67 in Fig. 2 into the full line position thereof. As illustrated in Fig. 3, the dogs are so placed that when the dog 84 is engaged with a tooth of the pinion, the dog 85 will be in an intermediate position and vice versa.

When the parts of the device are in the position shown in Figs. 1 and 2, the movable jaw member 27 may be moved in and out by hand. When it is desired to support work in the device, the movable jaw member 27 is pulled outward so that the work may be placed between the stationary and movable jaws 12 and 28. The movable jaw member is then moved inward until both jaws contact the work. The operator forces downward on the main operating pedal 58, thus swinging it from the position shown in full lines in Fig. 2 into the dotted line position 67, or into the position shown in Fig. 4. This causes the movable jaw member 27 to move in a rightward direction and causes the work to be gripped sufficiently to hold it so that it will not fall from place. This grip, however, is not strong enough to support the work if any strenuous action is to be done thereon.

The important part of my invention will now be described.

Pivoted on the shaft 76 on opposite sides of the pinion 77 but inside the walls 75 are yoke arms 90 and 91. The forward ends of the yoke arms 90 and 91 are attached together by a cross bar 92 which extends across the forward lower end thereof. Carried by the forward ends of the arms 90 and 91 is a pivot pin 93 on which an operating dog 94 is placed, the operating dog 94 being caused to resiliently engage the teeth of the pinion 77 by a suitable leaf spring 96. The yoke construction comprising the yoke arms 90 and 91 and the cross bar 92 is held in the position shown in Fig. 3 by means of a coil spring 97 which is compressed between a projection 98 of the release lever 71 and a projection 99 which is extended from the yoke arm 91. The projection 99 provides a shoulder 100 which engages an upper face of one of the walls 75 of the release lever 71 for determining the lowest swung position of the yoke construction.

Extended forwardly on opposite sides of the opening 59 are lugs 103 which support a shaft 104. Pivoted on the shaft 104 is a secondary lever 105 having a foot pedal 106. An arm 103 is extended from the lever 105 into a position below the forward part of the yoke construction so that it may engage the forward ends of the yoke bars 90 and

91 and the cross bar 92. After the main operating arm 57 has been moved into the position shown in Fig. 4, by forcing downward upon the main pedal 58, the secondary lever 105 is operated by the foot which engages the pedal 106. The secondary lever 105 is forced downward from the position shown in Fig. 3 into the position shown in Fig. 4. This moves the arm 103 upward from the position shown in Fig. 3 into the position shown in Fig. 4. The yoke construction is at this time moved from the position shown in Fig. 3 into the position shown in Fig. 4 against the action of the spring 97. By reason of the fact that the operating dog 94 is engaged with the pinion 77, the pinion will be rotated. The pinion, since it is in engagement with the rack 78, moves the operating arm farther in a rearward direction as indicated by dotted lines 108 in Fig. 4. This forces the dog 47 which engages the rack 51 of the movable jaw member 27 rearward a slight distance, which causes the stationary and movable jaws 12 and 28 to powerfully grip the work.

The yoke construction and secondary lever are returned to the position of Fig. 3 by the spring 97.

It is possible to obtain a very powerful grip by reason of the fact that the leverage obtained through the use of the secondary lever 105 is very great. The leverage of the lever 105 and the arm 103 is about five to one and the leverage of the yoke and the pinion 77 is about two to one. This is a much greater leverage than is obtained through the use of the pedal 58. The leverage obtained when using the secondary lever 105 is the leverage of the main operating arm multiplied by the leverage of the secondary lever 105 and the parts which connect it to the rack 78. When the work is to be released the release pedal 73 is depressed. The release lever 71 is moved downward from the position shown in the drawings against the action of the spring 80 so that the pinion 77 is removed from engagement with the rack 78. The coil spring 60 associated with the main lever 57 at this time returns the main lever to the full line position shown in Fig. 2 and in Fig. 3. The other parts of the vise are returned to corresponding position as shown in Fig. 2. The movable jaw member 27 is then entirely released and may be manually moved from contact with the work, the work then being easily removed.

As pointed out in the statement of invention, the important object of this invention is to provide a foot-operated vise which has a powerful grip. This object is accomplished by the use of the secondary lever 105 and the yoke assembly which rotates the pinion 77. These parts which are so im-

portant to the invention may be in proportion so that any leverage may be obtained and thus any degree of grip may be obtained.

I claim as my invention:

1. In a foot-operated vise, the combination of: a body having a stationary jaw; a movable jaw member having a movable jaw adapted to cooperate with said stationary jaw for gripping work; mechanism for moving said movable jaw towards said stationary jaw so as to grip the work; a main operating lever for operating said mechanism; and secondary mechanism for further actuating said main operating lever so that said movable jaw may be moved to rigidly grip said work. 70

2. In a foot-operated vise, the combination of: a body having a stationary jaw; a movable jaw member having a movable jaw adapted to cooperate with said stationary jaw for gripping work; mechanism for moving said movable jaw towards said stationary jaw so as to grip the work; a main operating lever for operating said mechanism; a rack carried by said main operating lever; a secondary lever; means operated by said secondary lever; and a pinion engaging said rack, said pinion being operated by said means for further actuating said main operating lever so that said movable jaw may be moved to rigidly grip said work. 75

3. A combination as defined in claim 2 in which said means comprises: a pivot yoke swung by said operating lever; and an operating dog carried by said pivoted yoke, said operating dog engaging and rotating said pinion. 95

4. In a foot-operated vise, the combination of: a body having a stationary jaw; a movable jaw member having a movable jaw adapted to cooperate with said stationary jaw for gripping work; mechanism for moving said movable jaw towards said stationary jaw so as to grip the work; a main operating lever for operating said mechanism; secondary mechanism for further actuating said main operating lever so that said movable jaw may be moved to rigidly grip said work; and release means for disengaging said secondary mechanism from said main operating lever so that said movable jaw is released from gripping engagement with the work. 105

5. In a foot-operated vise, the combination of: a body having a stationary jaw; a movable jaw member having a movable jaw adapted to cooperate with said stationary jaw for gripping work; mechanism for moving said movable jaw towards said stationary jaw so as to grip the work; a main operating lever for operating said mechanism; a rack carried by said main operating lever; a secondary lever; means operated by said secondary lever; and a pinion engaging said rack, 110

120

125

130

4
said pinion being operated by said means for further actuating said main operating lever so that said movable jaw may be moved to rigidly grip said work; and release means for disengaging said pinion from said rack so that said main operating lever may move in such a manner that said movable jaw will be released from gripping engagement with the work.

19 6. A combination as defined in claim 5 in which said release means consists of a release lever and in which said pinion is carried by said release lever.

7. In a foot-operated vise, the combination 15 of: a body having a stationary jaw; a movable jaw member having a movable jaw adapted to cooperate with said stationary jaw for gripping work; mechanism for moving said movable jaw towards said stationary jaw so as to grip the work; a main operating lever for operating said mechanism; a rack carried by said main operating lever; a secondary lever; means operated by said secondary lever; a rack engager engaging said rack, said rack engager being operated by said means for further actuating said

main operating lever so that said movable jaw may be moved to rigidly grip said work.

8. In a foot-operated vise, the combination of: a body having a stationary jaw; a movable jaw member having a movable jaw adapted to cooperate with said stationary jaw for gripping work; mechanism for moving said movable jaw towards said stationary jaw so as to grip the work; a main operating lever for operating said mechanism; a rack carried by said main operating lever; a secondary lever; means operated by said secondary lever; a rack engager engaging said rack, said rack engager being operated by said means for further actuating said main operating lever so that said movable jaw may be moved to rigidly grip said work; and release means for disengaging said rack engager from said rack so that said main operating lever may move in such a manner that said movable jaw will be released from gripping engagement with the work.

In testimony whereof, I have hereunto set my hand at Los Angeles, California, this 28th day of September, 1926.

GLEN W. MORGAN.
